UNITED STATES PATENT OFFICE.

JAMES B. SPENCER, OF SYRACUSE, NEW YORK, ASSIGNOR TO UNITED STATES HOFF-MAN MACHINERY COMPANY, INC., OF SYRACUSE, NEW YORK, A CORPORATION OF NEW YORK.

MACHINE FOR PRESSING GARMENTS.

1,326,982.

Specification of Letters Patent.

Patented Jan. 6, 1920.

Application filed June 15, 1915. Serial No. 34,130.

To all whom it may concern:

Be it known that I, JAMES B. SPENCER, a citizen of the United States of America, and a resident of Syracuse, in the county of 5 Onondaga, in the State of New York, have invented new and useful Improvements in Machines for Pressing Garments, of which the following, taken in connection with the accompanying drawings, is a full, clear, and 10 exact description.

This invention relates to certain improvements in machines for pressing garments and other fabrics and is similar in some respects to that shown in the patent to A. J. 15 Hoffman, No. 928,199, issued July 13, 1909, in that the garment is moistened, shaped and dried in one and the same operation by the simultaneous application of steam and mechanical pressure thereto through the 20 medium of two pressing elements, one of which is movable toward and from the other about an axis parallel with and some distance to the rear of the pressing elements.

The present improvement consists broadly 25 in providing a machine of this type with means by which the drying of the garment is greatly accelerated by the use of a suction device for the purpose of instantly withdrawing any steam or moisture of condensation with which the garment or buck may be 30 saturated after being subjected to the simultaneous application of steam and mechanical pressure.

The main object, therefore, of my invention is to provide a simple and comparatively inexpensive suction device which may be made as a unitary part of the machine and operated by steam from the same source of supply as that which is used for moistening the garment.

In other words, I have sought to produce in the same machine the necessary suction for instantly withdrawing the steam and moisture from the garment and pressing elements by causing a jet of steam, controlled at will, to be projected across the end of a suitable suction pipe communicating with the perforations in the press plate of one or both of the pressing elements so as to accelerate the drying of the garment and also of the pads or press cloths which may cover such perforated press plates.

Other objects and uses relating to specific parts of the suction device and its connection

with the pressing elements will be brought out in the following description.

In the drawings—

Figure 1 is a top plan of a portion of a garment pressing machine, embodying the features of my invention.

Fig. 2 is an enlarged transverse vertical sectional view, taken on line 2—2, Fig. 1.

Fig. 3 is a top plan of a portion of the buck showing a part of the perforated press plate and also a part of the suction chamber 65 with which the suction device communicates.

Fig. 4 is an enlarged detail sectional view of a modified form of suction device in which the same jet of steam is passed through two co-axial nozzles extending across the adjacent ends of the suction device leading to the suction chamber of the buck for producing double suction by the same jet of steam, or in the same operation.

Fig. 5 is a transverse vertical sectional 75 view of a clothes pressing machine, showing a further modified means for admitting and withdrawing the steam to and from the buck.

The machine illustrated comprises a buck 80 —1— and a press head —2—, the latter being mounted upon a vertically movable rock arm —3— which is hinged at —4— upon a portion of the main supporting frame —5— to swing about an axis parallel with the longitudinal centers of the buck and head and some distance to the rear thereof so as to leave a clear open space entirely around the marginal edges of the buck for spreading a garment thereon when the head is raised 90 preparatory to pressing.

The buck is shown as provided with non-communicating chambers —6— and —7—, serving, respectively, as a heating chamber 95 —6— being supplied with steam for heating purposes through a main supply pipe —8— having a branch —9— provided with a nozzle —10— discharging into a waste pipe —11— across the mouth of a suction pipe 100 —12— to produce suction in the latter.

This suction pipe —12— is provided with branches —13— leading to different portions of the chamber, which will hereafter be termed the suction chamber.

The branch pipe —9— is provided with a normally closed self-closing valve —14— of any well-known construction adapted to be

opened at will by any suitable means, such as a pedal lever —15— and a link —16— connecting said pedal lever with the valve stem, so that when the pedal lever is depressed the valve will be opened to allow the steam to pass through the suction nozzle —10— for producing more or less suction in the chamber —7—.

The buck is provided with a perforated 10 press plate —17— which also forms the upper wall of the suction chamber —7— and is covered by a foraminous pad or press cloth —18— so that any suction which is produced in the chamber —7— will act 15 through the perforated plate and press cloth directly upon the garment for withdrawing any steam or moisture of condensation from both the garment and press cloth or pad, thereby accelerating the drying of the same 20 instantly following the simultaneous application of steam and mechanical pressure to such garment.

The steam which is constantly present in the heating chamber —6— serves to keep the 25 head in a heated condition at all times to further facilitate the drying and shaping of the garment, the moisture of condensation which may accumulate in the chamber —6— being drawn off at intervals when necessary 30 through a drainage pipe —19—.

In this machine, the steam for moistening the garment is also introduced into the distributing chamber —7— through an inlet —20— which may be connected by a pipe 35 —21— to the same source of steam supply as that to which the pipe —8— is connected, the supply pipe —21— being provided with a self-closing valve —22— adapted to be opened at will by a suitable operating member —23—.

A baffle plate —24— extends across the inner end of the inlet —20— to distribute the steam across the entire area of the perforated press plate —17— so that such 45 steam may be applied uniformly to the garment while the latter is under mechanical pressure by the downward movement of the head —2— in the usual manner.

In some instances, I may desire to withdraw 50 the steam and moisture from the garment through the head instead of through the buck, as previously described, and for this purpose, I have provided another steam supply pipe —25— which may be connected 55 to the same source of steam supply as the pipes —8— and —21— and is provided with two branches —26— and —27— leading, respectively, to non-communicating chambers —28— and —29— in the head —2—, the 60 chamber —28— being in constant communication with the source of steam supply for keeping the head in a heated condition to accelerate the drying of the garment, while the branch —27— is provided with a suction nozzle —30—, similar to the nozzle 65

—12—, and leading into a waste pipe —31—.

Connected to this nozzle is a suction pipe —32— having opposite branches —33— communicating with different portions of the suction chamber —29—.

The branch pipe —27— is provided with a self-closing valve —34— adapted to be opened at will by a suitable operating member —35— to permit the passage of steam 75 through the suction nozzle —30— for creating a greater or less degree of suction in the chamber —29—.

The press head —2— is provided with a perforated press plate —36— forming the 80 bottom of the suction chamber —29— so that when the valve —34— is opened the suction produced in the chamber —29— will withdraw the steam and moisture from the garment and also from the press cloth or 85 pad while the pressing elements are in their pressing position, thereby effecting a quick drying of the garment, it being understood that when the valve —34— is opened for producing suction in the chamber —29—, the valve —22— controlling the steam supply to the garment will be closed.

In Fig. 4, I have shown the suction nozzle —10— as discharging directly into a secondary, but somewhat larger suction nozzle 95 —10'—, which in turn discharges into a waste pipe —11'—, said suction nozzles being connected to suction pipes —13— leading to different portions of the suction chamber —7— and taking the place of the 100 suction pipes —13—, so that one jet of steam passing through both nozzles produces equal suction in each of the pipes —13'—.

The modification shown in Fig. 5 comprises a buck —40— and a press head 105 —41—, the buck being provided with a steam chamber —42— having a perforated press plate —43— covered by a suitable press cloth and constituting a foraminous pressing element through which the steam 110 may be projected between the pressing elements and upon the garment.

In this case, steam is supplied to the buck through a single pipe —44— which in turn is connected to a steam suction nozzle —45— 115 to which steam is admitted through a suitable pipe —46— having a self-closing valve —47—.

The nozzle —45— discharges into an outlet pipe —48— having a self-closing valve 120 —49—, the valves —47— and —49— being located at opposite sides of the pipe —44— leading to the buck —40—.

These valves are normally closed and may be opened at will by any suitable means, as 125 for example, a lever —50— and separate operating members as pedals —51— and —52— connected thereto.

It is now clear that by opening the valve —47—, steam will be admitted through the 130

nozzle —45— and pipe —44— into the steam chamber —42— of the buck for distribution to the garment for the purpose of slightly moistening and sterilizing the same 5 during the pressing operation, and that by opening both valves —47— and —49—, the steam will be directed through the nozzle —45— into the discharge pipe —48—, thereby producing sufficient suction in the pipe 10 —44— and buck to withdraw all the steam and water of condensation therefrom and discharge it through the pipe —48— which may be connected to any waste pipe, not shown.

15 This latter construction is particularly advantageous in that it simplifies the piping system, by reducing the number of parts and enables the device to be applied to any existing machine in which steam is supplied 20 either through the buck or press head, it being evident that the same device may be applied to the press head if the steam is admitted therethrough to the garment.

What I claim is:

- 25 1. A garment pressing machine having a steam chamber communicating with the space between the pressing elements for supplying steam to a garment in said space, a valve for controlling the passage of steam 30 to said chamber, a steam-operated suction device connected to said chamber for removing steam from said garment and a valve for controlling the passage of steam to the suction device.
- 35 2. In a machine for pressing garments, a steam distributing system having means including a normally closed valve openable at will for applying steam to a garment in the machine, steam operated means forming a 40 part of the same system for withdrawing the steam from the garment and a normally closed valve openable at will for controlling the passage of steam to said withdrawing means.
- 45 3. In a garment pressing machine, a steam distributing system having means including a normally closed valve openable at will for applying steam to a garment in the machine, said system including a steam ejector for withdrawing the steam from the 50 garment and a normally closed valve openable at will for controlling the passage of steam to the ejector.
- 55 4. In a machine for pressing garments, the combination of lower and upper pressing elements having internal heating cham-

bers, one of said elements having a steam distributing chamber, means for supplying steam to all of said chambers including a normally closed valve openable at will for 60 controlling the steam supply to the distributing chamber, and a steam-operated suction device having its pressure side connected to the source of supply for said chambers and its suction side connected to 65 the distributing chamber, the connection of said suction device with the source of steam supply having a normally closed valve openable at will for controlling the flow of steam thereto.

70 5. In a machine for pressing garments, the combination of lower and upper pressing elements having internal heating chambers, one of said elements having a steam distributing chamber, steam pipes leading 75 to said chambers, one of said pipes having a normally closed valve openable at will, a steam-operated suction device having its pressure side connected to one of said pipes and its suction side connected to the distributing chamber, and a normally closed valve openable at will for controlling the 80 passage of steam to said suction device.

85 6. In a garment pressing machine, a buck having a heating chamber and a distributing chamber, the latter opening to the exterior of the buck, steam pipes leading to said chambers, a steam operated suction device having its pressure side connected to one of said pipes and its suction side 90 connected to the distributing chamber, and a normally closed valve controlling the passage of steam to the suction device and openable at will.

95 7. In a garment pressing machine the combination with a pair of pressing elements adapted to be drawn together to press a garment, one of said elements having a foraminous surface, of a steam distributing system having means for applying steam to the 100 garment at the pressing surfaces and said steam distributing system including therein a suction device for withdrawing moisture from the garment through the pressing element having the foraminous surface.

105 In witness whereof I have hereunto set my hand this 10th day of May, 1915.

JAMES B. SPENCER.
